UNITED STATES PATENT OFFICE.

CASPAR W. METTLER AND ADOLF METTLER, OF HARTFORD, CONNECTICUT, ASSIGNEES TO FREDERICK C. ROCKWELL, OF WEST HARTFORD, CONNECTICUT.

SOAP-BUBBLE BLOWER.

SPECIFICATION forming part of Letters Patent No. 690,028, dated December 31, 1901.

Application filed April 17, 1901. Serial No. 56,817. (No model.)

To all whom it may concern:

Be it known that we, CASPAR W. METTLER and ADOLF METTLER, citizens of the United States, residing at Hartford, in the county of 5 Hartford and State of Connecticut, have invented certain new and useful Improvements in Soap-Bubble Blowers, of which the following is a specification.

This invention relates to those articles of 10 amusement which are used for the formation of soap-bubbles.

The object of the invention is to produce a simple and inexpensive article of this nature which can be manipulated by children for 15 forming bubbles without exercising skill and without wetting the person or soiling the clothes.

The article that is illustrated as embodying the invention has a head of flexible material 20 connected by a yielding neck with a stiff tubular stem, the head and neck being perforated in continuation of the opening through the stem, and the outer end of the perforation through the head having a recess that 25 will hold just the requisite amount of liquid for properly forming the desired bubble.

Figure 1 of the drawings shows a side view of the article. Fig. 2 shows a side view with a portion of the stem and the neck and head 30 in section; and Fig. 3 shows a side view, with a portion in section, of a modified form of the article.

The tubular stem 1 may be made any length of any suitable material, the stem of the article which the drawings represent being made of a piece of bamboo. The head 2 that is shown in Figs. 1 and 2 is formed of a disk of rubber. Connected with this head is a flexible neck 3, that is stretched upon the end 40 of the stem. A small perforation 4 is made through the head and neck, and in the head at the outer end of this perforation is a recess 5.

In the modified design represented by Fig.

3 there are four perforations 6 through the 45 head 7, and at the end of these perforations are recesses 8.

When the heads of these articles are thrust into a cup, bowl, or the like containing the bubble-producing liquid and are pressed 50 against the bottom of the receptacle, the flexible heads and necks yield to an extent and cause such a contraction of the openings in the heads and necks as to produce a slight suction, which draws just the right amount of 55 liquid into the recesses at the ends of the perforations through the heads to form the desired bubbles when the user blows into the mouth ends of the stems.

With an article having a single perforation 60 through the head but one bubble is blown at a time; but with an article having a plural number of perforations through the head a number of bubbles may be blown simultaneously. 65

This simple article can be manipulated without particular care and bubbles blown without liability of taking up too great a quantity of liquid and having it drip upon the hands or clothing of the user. 70

We claim—

1. A soap-bubble blower, consisting of a tubular stem, a flexible head, and a flexible neck connecting the head and the stem, with openings through the head and neck to the 75 opening through the stem, substantially as specified.

2. A soap-bubble blower, consisting of a tubular stem, and a flexible head connected with the stem, said head having a recess for 80 liquid in its outer face and a passage connecting the recess with the opening through the stem, substantially as specified.

CASPAR W. METTLER.
ADOLF METTLER.
